Patented May 3, 1927.

UNITED STATES PATENT OFFICE.

JACQUE C. MORRELL AND SALMEN COMAY, OF CHICAGO, ILLINOIS, ASSIGNEES TO
UNIVERSAL OIL PRODUCTS COMPANY, OF CHICAGO, ILLINOIS, A CORPORATION OF
SOUTH DAKOTA.

METHOD OF PURIFYING HYDROCARBON OILS.

No Drawing.

Application filed June 22, 1925. Serial No. 38,924.

This invention relates to improvements in method of purifying and refining hydrocarbon oils, and refers more particularly to a process adapted for the removal of deleterious compounds from the overhead distillation products produced in the distillation of hydrocarbon oils under heat and pressure.

The specific embodiment of the present invention is directed to the idea of subjecting these overhead products to reaction with a solution of copper hypochlorite to remove objectionable sulphur and other deleterious compounds which cause the oil to go off color on standing. These objectionable compounds are present in the oil and unless removed, will produce a product having an obnoxious odor and one which will show a positive doctor test, that is, will be sour when subjected to the doctor test.

The copper hypochlorite may itself be utilized as the sole refining agent, necessary with some types of oil. With other types of oil, the copper hypochlorite may be substituted for the usual plumbite treatment, said plumbite being litharge dissolved in caustic soda. The copper hypochlorite is adapted to be used as a refining agent, either alone or as a step in combination with the usual sulphuric acid and caustic soda treatment, and perhaps as an adjunct to the plumbite treatment.

One method of using the copper hypochlorite may be illustrated as follows: The oil may be subjected to reaction first with the copper hypochlorite which may be produced according to the following formula:

Sodium hypochlorite may also be used instead of the calcium salt as a starting agent. Common salt or sodium chloride may be used to maintain the copper hypochlorite in solution. An excess of sodium chloride is desirable.

We have described above one formula which may be used to produce the copper hypochlorite, but it is understood that there are many other methods of producing this refining agent, and the sole purpose of the illustrative formula has been to give one method.

As pointed out heretofore, the copper

hypochlorite may be used as the sole refining agent with some types of oil which do not require further refining. For instance, benzine distillates and gasoline from straight run crudes, that is crude oil or heavy oils which have not been subjected to the cracking process. The crude oils and other heavy oils themselves may also be subjected to treatment with copper hypochlorite to remove certain types of sulphur compounds, such as mercaptans, hydrogen sulphide and various sulphides with this solution.

The oil which has been subjected to treatment with the copper hypochlorite, may then be water washed to remove any traces of the reagent, although this is not necessary. The oil may then be subjected to the usual sulphuric acid treatment followed by treatment with caustic soda and may later be distilled preferably in the presence of steam. The order of treatment which has been found preferable to use with cracked hydrocarbon distillates is as above set forth, namely successive treatments with copper hypochlorite, sulphuric acid, caustic soda, intervening water washes, and final distillation preferably in the presence of steam. It may be found desirable to treat the overhead product of the steam distillation with dilute caustic soda.

The succession of treating steps above described, may be varied according to the results desired, and the type of oil to be treated. Applicants claim no invention in the use of sulphuric acid, caustic soda or the distillation with steam, nor in the order or succession with which these refining agents are introduced into the oil, the novel feature of this invention residing in the use of copper hypochlorite as a refining agent either alone or in combination with any or all of the other refining agents or mediums.

It has been found that distillation may be carried out in the presence of copper hypochlorite, producing beneficial results with certain types of oils. In other words, it is desirable with certain types of oils to subject the oil to reaction with the copper hypochlorite at an elevated temperature. We are aware that it is old to subject oil to reaction with calcium hypochlorite or sodium hypochlorite for refining oils.

To illustrate the difference between the

action of calcium and sodium hypochlorites as compared with the copper hypochlorites, it is pointed out that the undesirable sulphur compounds are removed as copper compounds when using cuprous hypochlorite. However, the hypochlorite radical may by itself produce as beneficial results as when used in the forms cited above.

From an economical standpoint, in addition to the advantageous effects upon the oil when using copper hypochlorite, it has been found that it results in a saving of acid used. The amount of sulphuric acid used in the standard methods of treatment has been reduced with some types of oil, from thirty to sixty percent. The marked reduction in the sulphur content of the finished oil is also noticeable.

We claim as our invention:

1. A method of purifying hydrocarbon oils, comprising subjecting the oil to reaction with copper hypochlorite in solution.

2. A step in a method of purifying hydrocarbon oils, comprising subjecting the oil to reaction with copper hypochlorite to remove objectionable compounds present in said oil.

3. A method of purifying hydrocarbon oils, comprising separately subjecting the oil to reaction with sulphuric acid, caustic soda, copper hypochlorite and distillation in the presence of steam to remove objectionable compounds from the oil and produce a commercial product.

JACQUE C. MORRELL.
SALMEN COMAY.
